UNITED STATES PATENT OFFICE.

A. GAPPER SOUTHBY, OF JERSEY, CHANNEL ISLANDS, ASSIGNOR OF ONE-HALF TO FREDERICK DELACOURT BLYTH, OF LONDON, ENGLAND.

MODE OF AND APPARATUS FOR MAKING ICE, REFRIGERATING, &c.

SPECIFICATION forming part of Letters Patent No. 331,457, dated December 1, 1885.

Application filed May 26, 1885. Serial No. 166,729. (No model.) Patented in England August 8, 1877, No. 3,017; in France December 22, 1877, No. 121,767; in Belgium December 22, 1877, No. 43,843, and in Germany February 12, 1878, No. 2,744.

To all whom it may concern:

Be it known that I, ANTHONY GAPPER SOUTHBY, a subject of the Queen of Great Britain, residing at Jersey, one of the Channel Islands, have invented new and useful Improvements in the Mode of and Apparatus for Making Ice, Refrigerating, Evaporating, and Desiccating, of which the following is a specification.

10 My improvements consist in pumping away the aqueous vapor produced by removing the atmospheric pressure from water or liquids, or substances containing water. For this purpose I use a pump or exhauster to produce 15 the necessary vacuum and draw away the watery vapor, and when it has been so drawn away I more or less compress it and prevent it from condensing in any part of the pump or exhauster by keeping all the parts coming in 20 contact with the vapor at a higher temperature than that at which the vapor condenses at the highest compression to which it is subjected. I use two or more pumps in succession, the first to draw off the vapor and com- 25 mence the compression; while one or more pumps in succession complete the compression to the desired amount, or, as in the sec- 30 ond method mentioned further on, relieve the first pump or pumps from the pressure of the atmosphere. I sometimes use for drawing off the vapor and commencing the compression one of the forms of pump called "rotary," 35 by preference using one which works without valves, or in which the valves are formed by the piston passing certain passages or pos- 40 sitions, but in all cases the pump must act by displacement, or by alternate suction and compression and not by the momentum of the fluid acted on. In these pumps the moving 45 parts are required to fit with great accuracy, and a high rate of speed is advisable to diminish the piston-leakage as much as possible, and the clearance at the outlet end of the action must be reduced as much as possible, and a valve should be added to this outlet to remove as much as possible the back-pressure on the piston while the vapor is being compressed. After the vapor has been drawn away from the water to be frozen or

refrigerated, or from the liquids or substances to be evaporated or desiccated, I employ two methods for getting rid of it.

First method. After the compression has been carried to a certain extent by the first pump, I still further increase the compression of the vapor by one or more pumps in succession, till the density reaches that of the atmosphere, when I allow it to escape, taking care that every part of the pumps and passages coming in contact with the vapor are kept at a sufficient temperature to keep it from condensing, and the vapor as it escapes from the pump may be used to keep up the temperature for this purpose. In the above the pumps in succession must be of a capacity to receive the vapor as compressed by the preceding pump—for instance, for the production of ice, allowing that approximately the vapor of water at freezing temperature is about one one-hundred-and-fiftieth of the pressure of the atmosphere, and that it will therefore have to be compressed to one one-hundred-and-fiftieth of its bulk to allow of its escaping into the atmosphere, I compress the vapor twelve and a quarter times by the first pump, where using two pumps, and the remaining twelve and a quarter times by the other pump, the second pump being of a capacity to hold the vapor compressed by the first, and the temperature at which it is advisable to keep the different pumps and at which good results will be obtained are, say, not less than 110° Fahrenheit for the first pump, and a boiling-temperature for the second, and proportionately for more pumps in the succession as to capacity and temperature, and the latter may be calculated by reference to a table of the elastic force of the vapor of water at different compressions and temperatures. The pumps may be of any good construction adapted for the purpose of producing a high vacuum. Two or more pumps similar to the first pump shown in the drawings of the second method of the proportions mentioned above, and connected together by pipes, the whole moved by cranks on a shaft driven by any sufficient power, will answer well.

Second method.—I condense the vapor as

drawn off and more or less compressed by the first pump in a condenser, cooled either by air or water, as is well understood. In this method I employ one pump to produce a more 5 or less perfect vacuum and remove the air from every part of the apparatus, and another pump to draw off the vapor and, by compressing it cause it to condense in the condenser, from which the condensed water may 10 be pumped by the air-pump or may be allowed to collect in a reservoir, from which it may be drawn at the end of the operation. To make this second method more easily understood, and to show the general arrangement of the 15 whole apparatus as here described, I have annexed drawings, in which—

Figure I is a sectional elevation of an apparatus for carrying out this second method, (which I have found to answer well,) adapted 20 for making ice by hand or small power, being fitted with ice-box and water-cooled condenser, described further on. Fig. II is a section, and Fig. III a plan, of an ice-box for larger requirements, which may be substituted for that 25 shown at Fig. I. Fig. IV is a modification of the former.

A, Fig. I, is the first pump for drawing off the vapor and compressing it a certain amount—say, twelve and a quarter times—30 which will cause it to condense freely in the condenser if at a maximum temperature of, say, 100° Fahrenheit and 2.45 inches of mercury pressure. In this pump the cylinder B is moved up and down by a connecting-rod and 35 crank, (which is not shown in the drawings for the sake of simplicity,) the vapor being admitted to it through the hollow stationary piston-rod C. On the end of this piston-rod is formed a double valve, D, with passage E 40 between for the vapor. F is the piston, which is made with a passage through the center and enlarged cavity in the middle, with valve-seats in the upper and lower flanges, against which the valves on the piston-rod are alternately pressed by the motion of the cylinder 45 B, so admitting the vapor for the up-and-down strokes through grooves cut in the valve-seats at G. This mode of actuating the inlet-valves I have found to answer well, and 50 some kind of actuation is advisable for these valves, especially in small machines and working at a fast stroke, as the density of water vapor at the freezing-temperature .2 of an inch of mercury is too small to move a substantial valve with desirable speed.

Many other forms of actuated inlet-valves suggest themselves. For instance, one form I have found to answer when using an oscillating cylinder are clack-valves suspended from 60 the top, (like the exit-valves at H, Fig. I,) the valves so placed on the top and bottom diagonally of the sides of the cylinder that they fall away alternately from their seats by their own weight, as the cylinder first inclines to one side, then to the other; or slide valves and gear 65 similar to those used for steam-engines may

be used, but in all cases taking care to have the passages from the valves to the cylinder of as small capacity as possible, as also the clearance between the piston and ends of the cylinder at the ends of the stroke.

H, Fig. I, are the exit-valves, which move automatically, as it is not desirable that they should move till the pressure inside the cylinder equals that in the condenser, or there 75 would be waste of power from back-pressure.

I, Fig. I, is the stuffing-box for the piston-rod, which must not leak air. For this purpose the whole stuffing-box may be enveloped in a vessel of oil, as is often done with air-pumps for the laboratory, or, as is shown at 80 H', a short piece of vulcanized india-rubber pipe fitting tightly round the piston-rod and well lubricated, is sprung over a short nozzle on the cylinder end, the india-rubber pipe 85 being kept from stretching lengthwise by a ring of metal fitting loosely over the piston-rod, held in position by short standards on the cylinder end, as shown. This plan I have found to answer well, if kept constantly lubricated, and where the piston-rod does not travel 90 at a high speed.

In the drawings the cylinder is shown surrounded by a jacket for hot water to supply the heat to prevent condensation in the cylinder by the vapor, and which is assisted by the heat absorbed through the sides of the passages c, connecting the ice-box M with the pump and from the water in the coil of pipe O, described further on, where the temperature in the passages is lower than that of the atmosphere, as in making ice. The temperature in the water-jacket may conveniently be maintained by steam or gas. The exit-pipes are shown connected with the condenser J, 100 which may be of any approved construction, by the flexible india-rubber pipe K, lined with wire; or, if stuffing-boxes are used, they may be rendered air-tight by surrounding them 105 with oil.

L, Fig. I, is the air-pump, which is shown single action. The atmospheric pressure on the piston of this pump, together with that on the piston-rod of the large pump, are made to balance the weight of the cylinder of the latter, 115 the small pump being on the down stroke when the large is on the up. Both pumps may be driven by cranks on a shaft, as is well understood, and if of the size of those shown in the drawings, which are to a quarter-scale, can be 120 driven slowly by hand or fast by power.

Too great care cannot be taken in the fit of the piston and valves of the large cylinder of these apparatus, although the difference between the pressures on the inlet and outlet 125 sides of the pump is so small, (say from one and a half inches to three inches of mercury, according to the temperature of the water in the condenser,) still the vapor is so rarefied that it will pass freely through the smallest 130 leak.

Many well-known forms of Archimedean,

pneumatic, and rotary pumps or exhausters suggest themselves as applicable for producing small differential pressures, such as are here required, the two former worked with a medium of very high boiling-point in vessels capable of withstanding the pressure of the atmosphere, the latter worked at high speeds to minimize the leakage; but all forms of pump working by the momentum of the elastic fluid 10 acted on are inadmissible.

It is convenient in working this apparatus to have vacuum-gages, one on the pipe leading to the inlet-valves, and for this the little siphon mercury-gage will answer well, and 15 one on the pipe leading from the exit-valves, for which one of the Bourdon form of gages will answer. It is the more convenient plan when starting these pumps, in order to get up the vacuum, to begin with the second pump of 20 the first method, or the air-pump of the second method. These pumps should therefore be able to be disconnected from the first pump, so that they may be able to be worked separately.

25 In applying my invention to different useful purposes, I use a variety of apparatus adapted to the different requirements, among which I especially mention the following: In making ice the water to be frozen or refrigerated need 30 only be placed in a vessel capable of withstanding the external pressure of the atmosphere and connected with the pump or exhauster; as, for instance, in this way a decanter partially filled with water may have 35 the water cooled or more or less turned to ice; but where large blocks of ice are desired, I prefer to proceed as follows: I place a vessel or vessels (afterward called the "freezing-vessel," of the form desired for the blocks of 40 ice, and which vessel may be made of any suitable material, such as zinc) in another vessel with an opening large enough to admit the freezing-vessel, which opening I close with a cover fitted perfectly air-tight, as is well 45 understood, and I prefer to cause the vapors as they are drawn away from the freezing-vessel to pass over the surface of that vessel on their way to the pump or exhauster.

I sometimes cool the water before it is admitted 50 to the freezing-vessel by passing the cold vapor from the freezing-vessel over a vessel or pipes containing or through pipes passing through it. In this case the water after it has been cooled may be allowed to run 55 into the freezing-vessel, either intermittently or in a small stream; or the water cooled by one operation may be used in a subsequent operation.

I sometimes more or less remove the air and 60 gases absorbed by the water to be frozen before it is admitted to the freezing-vessel by submitting it to a partial vacuum in another closed vessel. This may conveniently be done by connecting this latter vessel with the second pump of the first method or the air-pump of the second method.

In the drawings I have shown these three last processes more or less carried out in two different forms of apparatus, the first attached to the complete machine and adapted for small 70 requirements, the second at Figs. II and III for larger requirements.

In both the figures the same letters denote the same parts.

M is the freezing-vessel, which, in Fig. I, is 75 made of glass as a slow conductor of heat, but in Fig. II is made of metal insulated by the cold vapor passing over its surface, (by means of the diaphragm n,) which is only the case with the top of Fig. I.

N, Figs. II and III, is the vessel with air-tight cover n' to contain the freezing-vessel, the joint being made tight with an ordinary greased packing-ring of india-rubber, while in Fig. I the freezing-vessel is shown jointed at 85 the top by a short pipe of greased india-rubber sprung round it. The course of the vapor on its way to the pump is shown by arrows.

O is a coil of pipe for cooling the water to be frozen in Fig. I inclosed in the enlarged 90 pipe to the pump in Fig. II inclosed between the diaphragm n and the sides and back of the vessel N, in both cases so that the vapors pass over it on their way to the pump. This pipe O is connected at one end with the reservoir 95 of water P and at the other end with the valve Q, to regulate the admission of the water to the freezing-vessel. This valve must open direct into the vessel without any intermediate passage, or otherwise it will be liable to be closed 100 by the formation of ice. The reservoir P may be a closed vessel with a pipe leading from the upper part to the second pump or air-pump for the removal of the absorbed gases, the water being admitted to it by a cock. The vessel N, Fig. II, should be furnished with glass 105 sight-holes, as in vacuum-pans placed above the freezing-vessel.

The commencement of the formation of ice may be known by the vacuum increasing to 110 .2 of an inch of mercury in the gage on the inlet-pipe, and when the water is admitted to the freezing-vessel intermittently or in a small stream, and care is taken that it shall not lie at any depth on the top of the ice, it 115 may be known that all the water has been turned to ice by the vacuum increasing above .2 when the admission of the water has been stopped.

In applying my invention to refrigerating 120 liquids in the case of aqueous solutions—such as brewers' worts—they may be placed so as partially to fill a vessel connected with the pump or exhauster, and the aqueous vapor drawn away till the desired temperature is 125 obtained, the vessel being closed air-tight and made of sufficient strength to withstand the pressure of the atmosphere; or a sufficient length of pipe may be laid in a similar vessel partially filled with water, and water may be 130 passed through the pipe and cooled, so as afterward to be used for refrigerating in a re-

frigerator, as is well understood, or the liquid to be cooled may itself be passed through the pipe. In either case I prefer to cause the water or liquid to be refrigerated to enter the pipe at the top of the vessel and leave it at the bottom, the pipe being in the form of a series of flat helices or gridirons joined together and laid horizontally one above the other in the vessel, only the lower ones being covered by the water partially filling the vessel, so that the refrigeration of the water or liquids in the pipe may be commenced by the vapor on its way to the pump, and finished by the water evaporating at the lower part of the vessel, and this water in the vessel may have its freezing-point lowered by chemical admixtures, as is well understood.

In the case of refrigerating air it may be passed through pipes fixed in a similar vessel, preferably more or less perpendicularly, and the vessel and pipes may be very much of the form of a multitubular perpendicular steam-boiler, the air to be cooled being passed through the pipes, preferably in a downward direction, and materials may be added to the water, which must only partially fill the vessel, to lower its freezing-point, and when it is desired to cool the air below freezing-point means must be used—such as scrapers—to keep the lower part of the pipes free from rime.

In desiccating by this invention the substances to be desiccated may be laid on a tray or trays and placed in a vessel similar to the one described to contain the freezing-vessel, and the trays may be laid on gridirons of pipes, or on shelves formed like thin boxes, through which warm water may be circulated; or, the vapor drawn off from the substances to be desiccated, after it has been more or less compressed, may be passed through the gridirons of pipes or very thin boxes instead of the warm water, the other end of the pipes or sides of the boxes to that at which the vapor is admitted being connected with the air-pump. Fig. IV will further explain this arrangement, R being the trays and T the gridirons of pipes, k being the pipe from the pump or exhauster, and k' being that to the air-pump.

In using this apparatus caution is required, according to the nature of the substances to be desiccated, not to get up the vacuum in the vessel too quickly nor to draw away the vapor too fast, as in the case of organic substances the cells will be broken by their being subjected too quickly to a vacuum or to too rapid a subtraction of their watery constituents, and in the case of whole fruits the skins will be broken, especially where the skin is of slow permeability, and when freezing would be injurious the pressure of the vapor in the vessel must not be reduced too low or down to .2 of an inch of mercury.

In evaporating by this invention the liquids may be placed in a vessel similar to an ordinary vacuum-pan, and the vapor pumped away and warm water may be circulated, or

the vapor drawn off from the liquids may be passed through the pipes or steam-jacket. In the latter case the pipes or steam-jacket of the vacuum-pan must be connected with the air-pump so that the vacuum-pan will be in the position of the condenser J, Fig. I in the drawings, and where the liquid to be evaporated is of a viscid or sirupy nature the bottom of the pan should be of a very flat pattern, and the liquid to be evaporated not deep in it—say, not more than one foot in depth—or it is advisable to stir the liquid with a stirrer, as is well understood, as the expansive force of the vapor at low temperatures is too small to rise from any depth.

When the liquid to be evaporated is not damaged by a temperature below freezing-point, brine may be passed through the pipes or steam-jacket of the vacuum-pan and cooled by the evaporation of the frozen liquid, and the cooled brine may be used for making ice or refrigerating, or water may be placed in vessels closed to the pan and not filled so as to burst by the freezing of the water in them, and the liquid to be evaporated may be showered over the pipes or vessels, but so that it may never allow any thickness on them.

Although I have described and illustrated in the drawings hereunto annexed apparatus which I have found very suitable for carrying out my said invention for the various purposes herein set forth, I would have it understood that I do not limit myself to the use of the said apparatus for the carrying into effect the several modes or methods of freezing, refrigerating, evaporating, and desiccating herein described, as other similar apparatus may be used for the same purposes.

I therefore claim for the purpose of making ice, refrigerating, evaporating, and desiccating—

1. The described method of making ice, refrigerating, evaporating, and desiccating, consisting in drawing off the vapor arising from water or liquids, or substances containing vaporizable water, when placed in a vessel from which the pressure of the atmosphere has been removed, and compressing the vapor so arising to a pressure less than that of the atmosphere by means of a pump or exhauster heated so as to prevent the condensation of the vapor in any of its parts, then delivering the vapor so compressed to another similarly-heated pump, by which it is further compressed to the pressure of the atmosphere and expelled or delivered to one or more pumps in succession to be so compressed and expelled, substantially and for the purposes herein described.

2. The described method of making ice, refrigerating, evaporating, and desiccating, consisting in drawing off the vapor arising from water or liquids, or substances containing vaporizable water, when placed in a vessel from which the pressure of the atmosphere has been removed, and compressing the vapor so

arising to a pressure less than that of the atmosphere by means of a pump or exhauster heated so as to prevent the condensation of the vapor in any of its parts, then delivering 5 the vapor so compressed into a vessel from which the air is exhausted by an air-pump or delivering it to another one or more heated pumps in succession, by which the vapor is further compressed, and then delivered into 10 the exhausted vessel, then condensing the vapor by cooling the vessel either by water or air or by the evaporation of liquids or substances

undergoing concentration or desiccation, then removing the water of condensation from the vessel either by the air-pump or intermittently 15 by letting down the vacuum in the vessel, and drawing off the water, substantially and for the purposes herein described.
